UNITED STATES PATENT OFFICE.

ADOLPH A. FAUST, OF DES MOINES, IOWA, ASSIGNOR OF ONE-HALF TO
NATHAN B. LENTZ, OF SAME PLACE.

DESIGN FOR A JAR-WRENCH.

SPECIFICATION forming part of Design No. 28,941, dated June 28, 1898.

Application filed September 29, 1897. Serial No. 653,521. Term of patent 14 years.

To all whom it may concern:

Be it known that I, ADOLPH A. FAUST, a citizen of the United States, residing at Des Moines, in the county of Polk and State of Iowa, have invented a new and original Design for a Jar-Wrench, of which the following is a specification.

This invention relates to a new and original design for a jar-wrench; and it has for its object to provide a design of this character that shall be both useful and ornamental.

The leading feature of the design resides in a jar-wrench having a circularly-coiled wire body provided with a pair of circular loops of the same diameter and lying in parallel planes one above the other, the terminals of said wire body being deflected outwardly from the loops and having divergently-disposed handles.

In the drawings, Figure 1 is a perspective view of a jar-wrench embodying the here-

in-described design. Fig. 2 is a plan view thereof.

Referring to the accompanying drawings, the numeral 1 designates a circular-coiled ²⁵ wire body having separate circular loops 2, which are of the same diameter and are arranged one above the other in the same circular plane. The terminals 3 of the coiled body are deflected outwardly from the loops ³⁰ 2 and are provided with the divergently-disposed rounded handles 4.

What I claim is—

The design for a jar-wrench, herein shown and described.

In testimony that I claim the foregoing as my own I have hereto affixed my signature in the presence of two witnesses.

ADOLPH A. FAUST.
